UNITED STATES PATENT OFFICE.

BENJAMIN F. HOWARD, OF INDIANAPOLIS, INDIANA, ASSIGNOR OF ONE-HALF TO
JOHN W. STAUB, OF INDIANAPOLIS, INDIANA.

LUBRICATOR.

992,503.

Specification of Letters Patent. Patented May 16, 1911.

Application filed October 25, 1910. Serial No. 589,029.

To all whom it may concern:

Be it known that I, BENJAMIN F. HOWARD, a citizen of the United States, residing at Indianapolis, in the county of Marion 5 and State of Indiana, have invented certain new and useful Improvements in Lubricators, of which the following is a specification.

This invention relates to improvements in means for economically supplying lubricating oils to the surfaces of machinery subject 10 to friction in the presence of steam, and the object of the invention is to thoroughly atomize the oil and mix it with the steam before the mixture reaches the wearing parts 15 to be lubricated.

I accomplish the object of the invention by the mechanism illustrated in the accompanying drawings, in which—

Figure 1 is a view in side elevation of my 20 invention applied in operative position to a steam supply pipe. Fig. 2 is a view of same in end elevation, and Fig. 3 is a vertical section on the line 3—3 of Fig. 2.

Like characters of reference indicate like 25 parts throughout the several views of the drawings.

4 represents a pipe for supplying steam to a mechanism, such, for example, as an engine cylinder, in which is a reciprocating 30 piston, and 5 is a minor communicating pipe, through which a portion of the steam is diverted from the main-pipe 4.

6 is a steam box supported adjacent to the pipe 4 and communicating therewith 35 through the pipe 7. The pipe 5 enters the box 6 through the remote end of the latter and terminates within the box opposite the opening into pipe 7, with sufficient clearance between the end of pipe 5 and inner wall of 40 the box to permit the condensed steam to pass down freely and accumulate at the bottom of box 6.

Above the box 6 is an oil reservoir 8 having a plug 9 screwed into its bottom and 45 adjustable vertically. This plug is perforated and forms a nipple through which oil from reservoir 8 is discharged. The upper end of the plug 9 is provided with a conical seat for the correspondingly shaped lower 50 end of a needle valve 10. The valve 10 is screw-threaded and passes out through a threaded opening in the top of the reservoir

and is provided with a hand wheel 11 by which the needle valve 10 is screwed up or down to regulate the quantity of oil discharged through the plug-nipple 9. The top of the reservoir 8 has a removable cap in which the needle valve is mounted which permits the needle to be readily removed and affords access to the interior of the reservoir 55 for the purpose of cleaning the latter. It will be noted that the upper end of the plug 9 terminates above the bottom of reservoir 8 whereby sediment will accumulate around the plug and will not enter the nipple to 60 65 clog its discharge.

The nipple or plug 9 discharges into the open end of an oil-tube 12, which tube extends vertically through the wall of the pipe 5, to the interior of the latter and is bent 70 toward the discharge end of pipe 5 and is continued within the latter, parallel with it, and terminates adjacent to the end of said pipe 5.

Live steam passing from pipe 4 through 75 pipe 5, around the oil-tube 12, so heats and volatilizes the oil in said tube that it is discharged from the end of the tube in the form of a vapor which mixes readily with the steam discharging from pipe 5, and is 80 carried through the pipe 7 into the pipe 4, and therein against the opposite inner wall of pipe 4 and becomes thoroughly mixed with the steam passing through the latter.

A valve 13 is provided in pipe 5 to regulate the quantity and pressure of steam supplied through pipe 5. 85

The bottom of the steam-box 6 has a removable plug 14 by the removal of which access is afforded to the interior of the box 90 for the purpose of removing the water of condensation and any sediment and accumulated impurities. To permit this to be done without danger of back pressure of steam from pipe 4 through the pipe 7, the latter is 95 provided with a valve 16, by which communication through pipe 7 at such times, may be cut off.

The oil reservoir 8 is provided with a removable plug 17, which, when removed, 100 permits the reservoir to be filled with oil. This plug will have an air-vent 18 to prevent a vacuum in the reservoir which would interfere with the oil flow.

As a detail of construction I have here shown the oil reservoir and steam box 6 as cast integrally, both being closed by a removable front plate 19. This plate is provided with the sight openings 20 and 21 through which the quantity of oil and water in box 6 and reservoir 8, respectively, may be seen at any time.

Having thus fully described my invention, 10 what I claim as new and wish to secure by Letters Patent of the United States, is—

1. The combination, with a main steam conducting pipe, of a branch pipe therefrom, means for supplying oil and volatilizing it 15 by the heat of the steam of said branch pipe and for discharging the volatilized oil into the discharge from said branch pipe, and means for then discharging the volatilized oil and steam together into the main pipe.

2. The combination, with a main steam conducting pipe, of a branch pipe taking steam therefrom, an oil conducting tube close to the branch pipe whereby its oil is 20 volatilized by the heat of the steam in said branch pipe, said oil tube and branch pipe being coterminous at their discharge ends whereby the volatilized oil is discharged into the steam discharge from said branch pipe and a connecting pipe receiving said combined steam and oil vapor and discharging 25 into the main pipe.

3. The combination, with a main steam conducting pipe, of a steam box, a pipe connecting the steam box with said main pipe, the discharge from the steam box being 30 above the bottom of the latter to form a receptacle which will not be drained through said connecting pipe, a branch pipe taking steam from said main pipe and discharging 35 into the inlet of said connecting pipe, and an oil tube entering said branch pipe and discharging in the same direction with and into the discharge of said branch pipe.

4. The combination with a main steam 40 conducting pipe, of a steam box, a pipe connecting the steam box with said main pipe, a branch pipe taking steam from said main pipe and discharging in said steam box into 45 said pipe connecting the box and main pipe, and an oil tube located within said branch pipe having its discharge near the discharge end of the latter and entering through the wall of said branch pipe whereby its inlet is outside of said branch pipe.

5. The combination with a main steam 50 conducting pipe, of a steam box, a pipe connecting the steam box with said main pipe, a branch pipe taking steam from said main pipe and discharging in said steam box into 55 said pipe connecting the box and main pipe, an oil tube located within said branch pipe having its discharge near the discharge end of the latter and entering through the wall of said branch pipe whereby its inlet is outside of said branch pipe, an oil reservoir and

means for feeding oil in regulated quantities from said reservoir into said oil tube.

6. The combination, with a main steam 60 conducting pipe, of a steam box, a pipe connecting the steam box with said main pipe, a branch pipe taking steam from said main pipe and discharging in said steam box into 65 said pipe which connects the box and main pipe, means in said branch pipe for regulating the steam passage therethrough, an oil tube located within said branch pipe having its discharge near the discharge end of the latter and having its entering end passed through the wall of said branch pipe whereby its inlet is on the outside of the latter, an oil reservoir above the steam box, a nipple in the bottom of the oil reservoir having a seat for a needle valve in its upper 70 end, and discharging into the inlet end of the oil tube, and a needle valve operating in conjunction with the seat in said nipple for regulating the supply of oil from said reservoir to said oil tube.

7. The combination, with a main steam 75 conducting pipe, of a steam box, a pipe connecting the steam box with said main pipe, a clean-out plug in the bottom of said steam box, a branch pipe taking steam from said main pipe and discharging in said steam box into 80 said pipe which connects the box and main pipe, a valve in said branch pipe to regulate the steam passage therethrough, an oil tube located within said branch pipe and extending for its major portion longitudinally of the latter and having its discharge 85 near the discharge end of the said branch pipe and entering through the wall of said branch pipe from above, an oil reservoir located above the steam box, a nipple adjustable vertically through the bottom of the oil reservoir and having a conical valve seat at its upper end and discharging into the 90 said oil tube, a needle valve passing through the top of the oil reservoir and adjustable from the outside in the conical seat in said nipple, the walls of the oil reservoir and steam box having sight holes.

8. The combination, with a main steam 95 conducting pipe, of a box having a horizontal partition dividing it into an upper oil reservoir and a lower steam box, a pipe connecting the lower or steam chamber with said main pipe, means in said connecting pipe for closing the discharge therethrough, the sides of said oil and steam compartments having sight openings, a branch pipe taking steam from said main pipe and discharging in said steam box into said pipe connecting the box and main pipe, an oil tube extending 100 downwardly through the top of the branch pipe, within the steam box, and thence extending within the branch pipe and longitudinally thereof to the discharge end of said branch pipe, a vertically adjustable nipple in the bottom of the oil reservoir dis- 105

charging into the said oil tube and having a valve seat at its upper end, and a needle valve operating in conjunction with the valve seat in the plug, said needle valve being adjustable from the outside of the oil reservoir.

In witness whereof, I have hereunto set

my hand and seal at Indianapolis, Indiana, this 15th day of October, A. D. one thousand nine hundred and ten.
